MILTON O. SCHUR, OF BERLIN, NEW HAMPSHIRE, ASSIGNOR TO BROWN COMPANY, OF BERLIN, NEW HAMPSHIRE, A CORPORATION OF MAINE.

BURSTING-STRENGTH TESTER FOR SHEET MATERIAL.

Application filed November 9, 1921. Serial No. 514,044.

This invention relates to machines for testing the bursting strength of sheet material such as paper, pulp, fabric and the like. One type of machine commonly used for this purpose known as the Mullen tester makes use of a flexible diaphragm subjected to hydraulic pressure and acting to burst the sheet through a die opening in one of a pair of clamping disks, a maximum pressure gage indicating the maximum hydraulic pressure exerted against the sheet. The test area of this machine is quite large having a diameter of $1\frac{1}{4}$ inches so that comparatively few tests are possible on a given area of sheet. When testing pulp also, this large area is found to give considerable variation between individual tests, the material tending to tear irregularly. Moreover it is found that a considerable variation in reading may be produced by varying the rate at which pressure is applied to the diaphragm.

The present invention relates to a machine of the Mullen type. As the test area of the Mullen machine is larger than desirable for testing pulp this invention contemplates a modified construction which requires a much smaller test area. In order that this may be satisfactorily accomplished the diameter of the die through which the diaphragm is projected in bursting the sheet is reduced to substantially $\frac{1}{2}$ inch while the diaphragm itself is much larger than this so that the area stretched as the pulp bursts is much more extended. This not only increases the life of the diaphragm but also reduces the pressure required to stretch the diaphragm alone to such a low figure compared to that required to burst the pulp that it becomes a negligible factor in the gage reading.

A further feature relates to improved means for clamping the sheet in the machine by which it is securely held. For this purpose at least one of the clamping members is coated with an abrasive such as sandpaper which engages the surface of the sheet.

A further feature of the invention relates to power means applicable both to the Mullen machine and the machine modified as above described by which the increase of pressure on the diaphragm is effected at

a uniform rate so that variability of readings due to variable rates of applying the pressure is eliminated. This mechanism also eliminates the tiresome hand operation necessary with the Mullen tester as previously constructed which is an item of considerable importance where much testing is required.

A further feature relates to a control mechanism by which connections between the pressure mechanism and the tester are automatically controlled, being made operative on the starting of the pressure increasing mechanism and rendered inoperative as soon as the sheet material bursts.

Further objects and advantageous details and combinations of parts will appear from a more complete description of an embodiment shown in the accompanying drawings in which—

Figure 1 is a front elevation partly in section and partly broken away of the entire mechanism.

Figure 2 is a side elevation partly in section of the tester mechanism.

Figure 3 is a top plan of the pressure applying mechanism.

Figure 4 is an end elevation partly broken away of the same mechanism.

Figure 5 is a sectional detail of a safety device forming a part of the pressure applying mechanism.

Figure 6 is a rear elevation of this mechanism.

Figure 7 is a detail plan of the belt shifter for this mechanism.

Referring first to Figure 2 at 1 is indicated a standard for supporting the testing mechanism. This standard has an arm 2 projecting horizontally therefrom which is formed with a hollow table portion 3. Fitted with in this table portion is a plug 4 having a small central perforation 5 therethrough opening at its upper end into a recess 5' surrounded by an annular rim 6. Fixed by cement to the upper face of the rim 6 is a rubber diaphragm shown at 7, the under face of this diaphragm being subjected to fluid pressure through the perforation 5 and the recess 5'.

Positioned above the diaphragm is a plate 100

8 having a central die opening 9 substantially smaller than the area within the rim 6 and through which the diaphragm may be distended when subjected to pressure on its lower face. This plate 8 is of comparatively thin material above the diaphragm but has a marginal thickened portion 10 which projects downwardly over the outer face of the table 3. The upper edge of the plate 8 has a marginal rabbet 11 to receive an inwardly directed flange 12 on a clamping sleeve 13 which has threaded engagement at its lower end with the outer face of the table 3. A rubber gasket 14 may be positioned between the upper face of the table 3 and the marginal portion 8 of the plug 4 so that a tight sealing joint may be made between the hollow arm 2 and the diaphragm by turning the sleeve 13 to bring the plate 8 downwardly.

The plate 8 is one of a pair of clamping plates between which the material to be tested is placed. The other clamping plate is shown at 15 and is supported from a plurality of arched arms 16 which unite at their upper ends in a collar 17 carried at the lower end of a plunger 18. This plunger 18 is vertically slideable in an arm 19 carried by the standard 1 and projecting over the arm 2. The plunger 18 has a head 20 at its upper end and bearing beneath this head and surrounding the plunger is a spring 21 seated in a socket 22 in the arm 19. The head 20 has a circular opening therein in which is journaled a cylindrical head 23 carried by an arm 24 which extends rearwardly between a pair of spaced upwardly extending jaws 25 carried by the arm 19 and the rear end of which rests on the upper end of a coil spring 26 supported on a fixed boss 27. The plunger 18 may be depressed to clamp the sheet material between the plates 15 and 8 by a clamping lever 28 pivoted at 29 between the jaws 25 and having a cam face 30 engaging the upper surface of the arm 24. Spring 21 is comparatively light and serves only to lift the upper clamping plate when lever 28 is raised.

50 The plate 15 has a die opening 33 having a dome-shaped upper end which limits the movement of the diaphragm when the sheet bursts and substantially mating the opening 9 of the plate 8, and its lower face surrounding the die opening is coated with abrasive 55 such as a ring of sandpaper 150 to firmly grip the adjacent face of the sheet material. The two clamp surfaces are preferably ground together until absolutely plane before the sandpaper is attached to one of them. Slidable in this opening 33 is a pin 60 34, the lower end of which is impinged by the diaphragm when the sheet material bursts. This pin 34 is carried by a lever 35, the outer end of which, as the pin is 65 raised, impinges against a spring contact

36 and forces it against a contact 37 on one of a pair of binding posts 38. These binding posts form part of a circuit designed to interrupt the supply of fluid pressure to the lower face of the diaphragm as will be later described.

Communicating with the hollow of the arm 2 beneath the plug 4 is a pressure supply pipe 40 and fixed thereto is a maximum pressure gage of any suitable description as 41, a push pin 42 being shown by which this gage may be returned to its zero position after pressure is removed. 75

Referring now to Figure 1 at 50 is shown a cylinder in which a liquid may be compressed. From the upper end of this cylinder projects a supply pipe 51 connected on one side through a needle valve 52, by which the opening for the passage of fluid may be constricted as desired, through a

check valve 53 which prevents flow backwardly toward the cylinder 50, to a three-way valve 54 which is preferably of a balanced non-leakable type. This valve is shown in section in Figure 2 and is designed in one position to open communication from the pipe 51 through the needle

and check valves to the pipe 40 leading to the lower side of the diaphragm. In another position of this valve the connection to the supply cylinder 50 is blanked while the pipe 40 is connected to an outlet pipe 55 which leads to a supply reservoir 56. From

which leads to a supply reservoir 56. From the lower end of this supply reservoir a pipe 57 leads through a check valve 58 to the pipe 51, this check valve permitting fluid to flow from the reservoir 56 to the cylinder 50 but preventing flow in the reverse direction.

As shown the three way valve 54 is moved to cut off the connection between the cylinder 50 and the diaphragm by means of a solenoid shown at 60, the core 61 of which acts against the arm 62 of the valve. This solenoid is in series with the binding post 11.

38 above described so that when the contact arm 36 bridges these posts the solenoid is energized and the valve turned to cut off communication between the cylinder 50 and the lower face of the diaphragm and to open communication between the lower face of the diaphragm through the outlet pipe 11.

or the diaphragm through the outlet pipe 55 to the reservoir 56. If desired the valve 54 might be operated by purely mechanical means being connected by links to the pin 51. The level of the liquid in the reservoir

34. The level of the liquid in the reservoir 56 is designed to be somewhat below the level of the diaphragm so that when connection is made to this reservoir a slight negative pressure will be developed in the 12

suction leg of liquid will be produced in the pipe 55 tending to draw the diaphragm downwardly from the die openings and clamping plate and to free it from the under face of the lower plate 8. This action insures that the diaphragm shall be 121

kept from sticking to the lower plate and will be out of the way for the sheet to be tested to be passed between the plates when the pressure is removed. Glycerine is preferably employed as the fluid by which pressure is transmitted to the diaphragm.

The needle valve 52 is interposed between the cylinder 50 and the testing mechanism in order to render the flow of liquid therebetween very slow. During the building up of pressure by the diaphragm the actual flow of liquid is slight since the movement of the diaphragm is slight. When the sheet bursts, however, the volume for liquid in the tester increases suddenly and due to the restricted flow through the needle valve the pressure therein immediately lowers since liquid may not flow sufficiently rapidly to immediately fill the increased space. This construction has been found of great importance, since with an unrestricted flow a water hammer effect may be produced from the sudden stopping of flow as soon as the distention of the diaphragm is stopped after the bursting of the sheet, this giving a momentarily increased pressure giving an incorrect reading on the pressure dial 41. The small size of the perforations 5 through the plug 4 also aids in restricting the flow to the diaphragm.

Means is provided by this invention for gradually and uniformly increasing the pressure on the fluid by power. This construction is shown more particularly in Figures 1 and 3 to 7, inclusive. Referring to these figures the cylinder 50 is seen to have movable therein a piston or plunger 601 which passes downwardly within a guide cylinder 611 on which the pressure cylinder 50 is supported. The lower end of this piston 601 has preferably fixed thereon a guide collar or disk 621 fitting within the guide member 611. The lower end of member 611 is supported on the top of a hollow post 63 projecting upwardly from a base 64. Positioned within this post 63 is a vertically slidable rack bar 65. This rack bar is reduced at its upper end at 66 and surrounding this reduced portion and bearing at one end against a shoulder 67 on the rack produced by this reduced portion is a spring 68 which bears at its opposite end against the under face of the disk 621. The reduced portion 66 is formed hollow for the slidable reception of the head 69 of a rod 70 which passes through a perforation 71 in the upper end of the rack bar, through the coil spring 68 and which is made fast at its upper end in the lower end of the piston plunger 601 at 72. It is evident that by pushing upwardly on the rack bar the force exerted on the spring 68 may be increased, while if by moving the rack bar downwardly the head 69 impinges against the upper end of the rack bar, the piston plunger 601 will be positively

lowered. By this latter action it is insured that a supply of glycerine is drawn inwardly from the reservoir 56 as needed to supply losses due to leakage or otherwise in the system so that the actual motion of the piston 601 will be through a very small amplitude and will start from the same position at each actuation.

The rack bar 65 is actuated by means of a pinion 75 fixed to a drive shaft 76. This shaft 76 is supported by suitable bearings from the pedestal 64 and carries at one end a worm gear 77 with which meshes a worm 78 fixed to a horizontally arranged shaft 79. As shown the worm and gear are 80 enclosed in a suitable casing 80. This shaft 79 has mounted thereon a pair of loose pulleys 81 between which is a fixed pulley 82. Adjacent to one of the loose pulleys 81 is also fixed a brake pulley 83. Leading 85 from the pulleys 81 and 82 and shiftable therebetween is a pair of drive belts shown at 84 which pass over a common drive pulley not shown. One of these belts is crossed so that when engaging the fixed pulley these 90 belts will drive shaft 79 in opposite directions. For the purpose of shifting these belts between the fixed and loose pulleys a double belt shifter shown at 86 has been provided. This shifter has two pairs of 95 oppositely extending shipping fingers 87 between which are passed the belts 84 and it is fixed to a bar 88 slidably mounted in parallel relation to the shaft 79. For this purpose guide fingers 89 are shown at one 100 end thereof and adjacent the other is fixed a guide plate 90. Adjacent to this guide plate the bar 88 has pivoted thereto a lever 91 fulcrumed at 92 on a link 93 pivoted at 94 to a bracket 95 which carries one of the 105 bearings for the shaft 79, this bracket being supported from the base 64. The lower end of the lever 91 is pivoted to a link 96 extending to a rocker arm 97. This rocker arm is fixed to a rock shaft 98 which extends 110 through the base 64 and which has fixed at its opposite end a double armed lever 99. Pivoted at the ends of this lever is a pair of treadles 100 which are maintained in parallel relation by means of a link 101 115 pivoted at its opposite ends thereto and fulcrumed at the point 102 on a bracket 103 fixed to the base 64. By this means it is seen that on depressing one or the other of the treadles 100 the belt shifter is moved to 120 bring one or the other of the belts 84 into driving relation to the shaft 79 to actuate the rack bar to increase or decrease the pressure exerted on the spring 68 and consequently the fluid pressure in the cylinder 50. 125

In order that the movement of the rack bar may be stopped automatically after sufficient movement in either direction to accomplish its required functions, a safety device to return the belts to their inactive 130

positions on the loose pulleys has been provided. For this purpose the post 63 is provided with an extension or boss 105 on which is threaded a collar 106. This collar projects beyond the end of the boss and has fixed thereto a key 107 slidable in a groove in the shaft 76. By this means the collar 106 must rotate with the shaft 76 but is moved axially of the boss 105 during such rotation. This collar 106 has fixed thereto a circular flange 108 which carries on opposite sides thereof a pair of arms 109 and 110. These arms are offset at their ends as shown more particularly in Figure 7, and are positioned one on either side of the belt shifter bar 88. On either side of this bar 88 are a pair of frusto-conical rollers 111 and 112 which are journaled on a bolt or stud 113 passing through the bar. Referring to Figure 7 it is noted that the arm 109 is in position to engage the roll 113 on rotation of the shaft 76 in a direction to move the arm 109 to the left, it being designed that in such position of the parts the bar 88 will be moved to shift the belts to stop the rotation of the shaft in this direction. It is also to be noted that as a reverse direction of rotation of the shaft 76 brings the arm 110 to the right, the end of this arm passes beyond the end of the roll 112. On a succeeding complete rotation of the shaft 76, however, the arm 110 is moved inwardly in position to contact the roll 112 due to the threaded engagement of the collar 106 with the boss 105 and it then shifts the bar 88 to the right to throw the driving belt for this direction of rotation on to the loose pulley. The arm 109 is now beyond the end of roll 113 so that on the first complete rotation of shaft 76 in the reverse direction it fails to move the bar 88 but on the next rotation it strikes the roll and shifts the belts to stop further rotation of the shaft. It is therefore seen that after two revolutions of the shaft 76 in either direction the power for rotating the shaft in that direction is cut off. In order to prevent the overrunning of the mechanism so that reverse rotation of the shaft is not initiated by the shifting of the bar 88, a brake mechanism is provided. This comprises a brake band 115 which passes partially about the brake pulley 83, being fixed to the machine frame at one end as shown at 116 (Figure 4), the other end thereof being attached to a yoke 118 through which passes a shaft 119 carrying a cam roll 120. This cam roll is supported from the bracket 90 in position to be contacted and raised by a cam plate 121 fixed to the bar 88. By this means when the bar 88 is shifted in either direction to bring the previously active belt on to the loose pulley the roll 120 is raised and the brake band 115 tightened about pulley 83 to stop the mechanism.

If desired the valve 54 may be actuated

automatically to connect the pressure cylinder 50 with the lower side of the diaphragm on initiation of motion of the pressure increasing mechanism. For this purpose there is herein shown on Figure 2 a 70 solenoid 130 having a core 131 acting in opposition to the core 61 of the solenoid 60. This solenoid is preferably in a circuit controlled by a switch operated by the treadle mechanism. For this purpose a construction illustrated in Figure 6 may be provided. The bearing 89 for the bar 88 carries a post 132 of insulating material which carries a contact element 133. A bracket 134 extends outwardly from the post 132 and has pivoted 80 at its extremity a lever 135 also of insulating material. Fixed to the upper end of this lever is a spring arm 136 carrying a contact element 137 adapted to impinge against element 133 on rocking the lower end of lever 85 135 away from post 132. The closing of these contacts closes the electric circuit through the solenoid 130. These contacts are normally held apart by a spring 138 urging the lower end of lever 135 toward the 90 post 132. To this end, however, is pivoted a latch member 139 having a portion 140 arranged to contact the side of this lever to limit its upward pivotal movement relative thereto. The end of bar 88 has fixed thereto a plate 141, which, as the bar moves to shift the belts to start the operation of the pressure mechanism by pressure on the right hand treadle of Figure 1, contacts the lower end of member 139, rocks it upwardly until 100 the portion 140 contacts lever 135 and then turns this lever to establish contact between elements 133 and 137. The plate 141 then slips from beneath member 139 and the contacts are immediately separated by the 105 spring 138. On return of bar 88, the plate 141 passes beneath member 139, rocking it idly about its pivotal connection with the lever 135 sufficiently to permit this action 110 without affecting the contacts.

The sheet to be tested is inserted between the plates 15 and 8, the lever 28 being in raised position as shown in Figure 2, whereupon the lever 28 is pushed downwardly to bring the plate 15 against the upper surface 115 of the sheet. The right hand treadle 100 is then depressed, which as above described, through the solenoid 130 actuates the valve 54 to connect the pressure cylinder 50 to the lower side of the diaphragm. The pressure within the cylinder 50 is then gradually and uniformly increased as the rack bar 65 is moved upwardly until the sheet bursts and the diaphragm stretches within the die opening 33. When this takes place the electrical 120 connections are closed through the solenoid 60 whereupon this solenoid is actuated to shut off the connection to the diaphragm from the pressure cylinder 50 and to open the connection from the diaphragm to the 130

reservoir 56. The left hand treadle 100 as shown in Figure 1 is then depressed to return the rack bar to its initial position to relieve the pressure on the hydraulic system and to fill the cylinder 50 from the reservoir. The apparatus is then in position for repetition of the same cycle. The pressure at which the bursting of the sheet has taken place is then read directly from the gage 41 which may be returned to zero by pressure on the release button 42. Overtravel of the rack in either direction is prevented by the arms 109 and 110 contacting and moving the bar 88 to its neutral position.

Having thus described an embodiment of this invention it should be evident to those skilled in the art that many changes and modifications might be made therein without departing from its spirit or scope as defined by the appended claims.

I claim:

1. A device of the class described comprising a pair of plates between which a sheet may be clamped, one of said plates having an opening therethrough, a flexible diaphragm free to stretch over an area substantially larger than that of said opening, and means for subjecting said diaphragm to fluid pressure to project it through said opening to burst the sheet.

2. A device of the class described comprising a lower clamping plate having an opening therethrough, a perforated plug positioned below said plate, a diaphragm fixed to the upper face of said plug and unattached thereto over an area substantially larger than the opening of said plate, an upper clamping plate having an opening in registry with the opening of said lower plate and by which a sheet may be clamped against said lower plate, and means for supplying fluid pressure to the lower side of said diaphragm through the perforation in said plug.

3. A device of the class described comprising a lower clamping plate having an opening therethrough, a perforated plug positioned below said plate, a diaphragm fixed to the upper face of said plug and unattached thereto over an area substantially larger than the opening of said plate, a collar for retaining said lower clamping plate against the upper face of said plug, an upper clamping plate having an opening in registry with the opening of said lower plate and by which a sheet may be clamped against said lower plate, and means for supplying fluid pressure to the lower side of said diaphragm through the perforation in said plug.

4. A device of the class described comprising means for applying pressure against one side of sheet material tending to burst the same, and means for increasing the

pressure insuring such increase at a uniform rate.

5. A device of the class described comprising means for applying pressure against one side of sheet material tending to burst the same, and power means acting to increase the pressure at a uniform rate.

6. A device of the class described comprising plates between which sheet material may be clamped, said plates having registering openings therethrough, a diaphragm subjected on one side to fluid pressure and engaging one side of the sheet material over the area defined by the opening in one of said plates, and means for increasing the pressure on said diaphragm at a uniform rate until said diaphragm bursts the sheet material.

7. In a device of the class described comprising means for holding a sheet, fluid pressure mechanism actuatable to burst the sheet, a fluid pressure supply adapted to be placed in communication with said mechanism, means acting to increase the pressure in said supply at a constant rate, and means actuated on the bursting of said sheet to disconnect said supply from said mechanism.

8. A device of the class described comprising means for holding a sheet, pressure responsive mechanism acting to burst the sheet, a source of pressure, a valve between said source and mechanism, magnetic means for closing said valve, and a switch actuated on the bursting of said sheet for controlling said magnetic means.

9. A device of the class described comprising in combination, means for holding a sheet, pressure responsive mechanism actuatable to burst the sheet, a fluid pressure supply, means for increasing the pressure of fluid in said supply, a valve controlling the communication between said supply and mechanism, means actuated on the initiation of said pressure increasing means for opening said valve, and means acting on the bursting of said sheet to close said valve.

10. A device of the class described comprising in combination, means for holding a sheet, pressure responsive mechanism actuatable to burst the sheet, a fluid pressure supply, means for increasing the pressure of fluid in said supply, a valve controlling the communication between said supply and mechanism, electroresponsive means for actuating said valve, a switch for controlling the opening of said valve actuated on the initiation of said pressure increasing means, and a switch for controlling the closing of said valve actuated on the bursting of said sheet.

11. A device of the class described comprising means for holding a sheet, fluid pressure mechanism actuatable to burst the sheet, a fluid pressure supply, means including a constricted portion for transmitting fluid

6
pressure from said supply to said mechanism, means for increasing the pressure of said supply, and means actuated on the bursting of said sheet for closing off said 5 transmitting means.

12. A device of the class described comprising in combination, means for holding a sheet, fluid pressure mechanism actuatable to burst the sheet, a fluid pressure supply 10 adapted to be placed in communication with said mechanism, means to increase the pressure of said supply, means to close the communication between said supply and mechanism after the sheet bursts, and a means 15 restricting the flow of fluid from said supply to said mechanism to prevent a momentary increase of pressure in said mechanism after the bursting of said sheet.

13. A device of the class described comprising in combination, means for holding a sheet, fluid pressure mechanism for bursting the sheet, a fluid pressure supply adapted to be placed in communication with said mechanism, means for increasing the pressure 20 of fluid in said supply, a fluid reservoir, and means acting after the bursting of said sheet for closing off communication from said supply to said mechanism and opening communication from said mechanism to said 25 reservoir.

14. A device of the class described comprising in combination, means for holding a sheet, fluid pressure mechanism for bursting the sheet, a fluid pressure supply adapted 30 to be placed in communication with said mechanism, means for increasing the pressure of fluid in said supply, a fluid reservoir, and means acting after the bursting of said sheet for closing off communication from 35 said supply to said mechanism and opening communication from said mechanism to said reservoir, the level of fluid in said reservoir being below said diaphragm to cause said diaphragm to be drawn away 40 from said sheet when said mechanism is connected to said reservoir.

15. A device of the class described comprising in combination, a fluid pressure cylinder, a piston movable therein, a spring 45 bearing on said piston, fluid pressure mechanism for testing material in communication with said cylinder, and means acting to increase the pressure exerted by said spring at a determined rate to correspondingly increase the fluid pressure in said mechanism.

16. In a device of the class described, a fluid pressure applying mechanism comprising a fluid pressure cylinder, a piston in 50 said cylinder, a spring acting on said piston, and power means acting to increase the pressure exerted by said spring at a predetermined uniform rate.

17. In a device of the class described, a 55 fluid pressure applying mechanism comprising

ing a fluid pressure cylinder, a piston movable in said cylinder, a guide member arranged axially of said cylinder, a bar movable in said guide member, a spring interposed between said plunger and piston, and 60 means for moving said plunger toward said piston at a predetermined rate to correspondingly increase the pressure of fluid in said cylinder.

18. In a device of the class described, a 75 fluid pressure container, power means acting to increase the pressure in said container at a predetermined uniform rate, and means acting a definite time after the starting thereof for stopping the operation of said 80 power means.

19. In a device of the class described, comprising a fluid pressure cylinder, a piston movable in said cylinder, a spring bearing at one end on said piston, a bar engaging the opposite end of said spring, a shaft, connections from said shaft to said bar whereby rotation of said shaft in opposite directions moves said bar toward and from said cylinder to increase or decrease the pressure of 90 fluid therein respectively, means for rotating said shaft, and means for reversing the direction of rotation of said shaft.

20. In a device of the class described, a 95 fluid pressure applying mechanism comprising a fluid pressure cylinder, a piston in said cylinder, a bar reciprocable in line with the axis of said piston, a spring interposed between said bar and piston, a shaft, a tight pulley and a pair of loose pulleys on said 100 shaft, a source of power, a pair of belts from said source to said pulleys arranged to drive in reverse directions, means for shifting said belts between said tight and loose pulleys to rotate said shaft in either direction at 105 will, and connections acting to move said bar toward and from said piston on reverse directions of rotation of said shaft.

21. In a device of the class described, a 110 fluid pressure applying mechanism comprising a fluid pressure cylinder, a piston in said cylinder, a bar reciprocable in line with the axis of said piston, a spring interposed between said bar and piston, a shaft, a tight pulley and a pair of loose pulleys on said 115 shaft, a source of power, a pair of belts from said source to said pulleys arranged to drive in reverse directions, means for shifting said belts between said tight and loose pulleys to rotate said shaft in either direction at will, connections acting to move said bar toward and from said piston on reverse directions of rotation of said shaft, and means to shift said belts to stop the rotation of said shaft 120 after a definite extent of rotation thereof in either direction.

22. A device of the class described comprising a pair of annular plates for clamping a sheet, means for bursting the sheet through one of said plates, and an abradant carried 125 130

by one of said plates in engagement with the sheet to insure a firm hold thereon.

23. A device of the class described comprising a pair of annular plates for clamping a sheet, a diaphragm on one side of said plates which may be subjected to fluid pressure to burst the sheet through said plates,

and a dome shaped element on the opposite side of said plates from said diaphragm to limit the movement of said diaphragm when the sheet bursts. 10

In testimony whereof I have affixed my signature.

MILTON O. SCHUR.
